UNITED STATES PATENT OFFICE.

CHARLIE E. GOLDSMITH, OF STREATOR, ILLINOIS.

RAIL-JOINT.

1,279,858.

Specification of Letters Patent. Patented Sept. 24, 1918.

Application filed January 11, 1918. Serial No. 211,356.

To all whom it may concern:

Be it known that I, CHARLIE E. GOLDSMITH, a citizen of the United States, residing at Streator, in the county of La Salle and State 5 of Illinois, have invented new and useful Improvements in Rail-Joints, of which the following is a specification.

My present invention pertains to rail joints, and consists in the peculiar and advantageous joint, hereinafter described and claimed, embodying fish-plates adapted to receive the bases and support the heads of adjoining rails, and a protective plate, calculated to bridge the joint so as to afford 15 a continuous wheel-support and prevent pounding, and also calculated to afford a strong resistance against lateral outward pressure against the inner sides of the adjoining portions of the rails.

20 In the accompanying drawings, which are hereby made a part hereof:

Figure 1 is a view, partly in transverse section and partly in end elevation, of my novel joint.

25 Fig. 2 is an elevation of the outer side of the joint.

Similar numerals of reference designate corresponding parts in all the views of the drawings.

30 The rails 1 are of the ordinary well-known type, and at opposite sides of the adjoining portions of the same are fish-plates 2. These latter have lower portions 3 that receive the bases of the rails, and upright portions 4 35 that bear at 5 on the rail bases and against the rail webs and at 6 against the undersides of the rail heads and against the webs, so as to strongly support the heads and adequately brace the upper portions of the webs against 40 lateral pressure.

Disposed on and against the outer fish-plates and also against the outer sides of the rail heads is the protective plate 8 which is preferably of rolled steel and of a length 45 sufficient to enable the clamps comprised in the joint to rest at opposite sides of a ten inch sleeper when the joint occurs over a sleeper. The said protective plate extends upwardly to a point slightly above the tread 50 portions of the rails and has beveled ends 9

in order to enable wheels to readily pass on the plate.

The clamps referred to comprise bolts 10 having hooked ends 11 adapted to engage one fish plate, nuts mounted on the threaded portions of the bolts, said nuts being numbered 12, and adjustable members 13 arranged on the bolts inside the nuts and arranged to engage the other fish plate.

It will be noted that the upright portion 60 of the protective plate bears on the adjacent fish plate, and hence the plate is adapted to adequately support a wheel incidental to the passage of the same over the joint between the rails.

Extending through elongated apertures in the protective plate and also extending through registering apertures in the fish plates and the webs of the rails are bolts 14, equipped with the ordinary, well known 70 nuts 15.

My novel joint in addition to the advantages hereinbefore ascribed to it is simple and inexpensive in construction and is well adapted to withstand the shocks and strains 75 to which rail joints are ordinarily subjected.

Having described my invention, what I claim and desire to secure by Letters Patent, is:

1. The herein described rail joint, comprising adjoining rails, fish-plates having lower portions constructed and arranged to receive the bases of the rails and also having upright portions interposed between the rail bases and heads and bearing adjacent to the bases and heads against the webs, a protective plate arranged against the outer sides of the rail heads and bearing on the lower portion of the outer fish-plate and also bearing against the outermost portion of the outer fish-plate, 80 bolts arranged transversely below the fish-plates and having hooks engaging one of the fish-plates and also having threaded portions, nuts on said threaded portions, connecting bolts extending through the rails and plates and clamping members mounted on the threaded portions of the bolts inside the nuts and engaging the other fish-plate. 85

2. In a rail joint, a protective plate arranged against the outer sides of the heads 90

of adjoining rails and bearing on an adjacent fish-plate, and bolted to the rails and fish-plates, and clamps having bolts extending below the fish plates and rails and 5 equipped to engage the oposite portions of the fish-plates.

In testimony whereof I have hereunto set

my hand in presence of two subscribing witnesses.

CHARLIE E. GOLDSMITH.

Witnesses:

R. M. BORGRIER,

W. L. SPRAGUE.
